CLAIM

The ornamental design for a peritoneal dialysis machine with user interface, as shown and described.

DESCRIPTION

FIG. 1 is a perspective view of the peritoneal dialysis machine with user interface showing the top, front and left sides thereof;

FIG. 2 is a perspective view of the peritoneal dialysis machine with user interface showing the top, front and right sides thereof;

FIG. 3 is a perspective view of the peritoneal dialysis machine with user interface showing the top, rear and right sides thereof;

FIG. 4 is a perspective view of the peritoneal dialysis machine with user interface showing the top, rear and left sides thereof;

FIG. 5 is a front side view thereof;

FIG. 6 is a rear side view thereof;

FIG. 7 is a left side view thereof;

FIG. 8 is a right side view thereof; and,

FIG. 9 is a top side view thereof.

The broken lines in the drawing views are included for the purpose of illustrating portions of the dialysis machine that form no part of the claimed design.

1 Claim, 9 Drawing Sheets
